LAMP

William F. Suden, 114 Webster Ave., Cranston, R.I.

Filed Mar. 31, 1964, Ser. No. 79,277

Term of patent 14 years

(Cl. D48—20)

FIG. 1

FIG. 2

FIG. 3

The dominant features of my design reside in those portions shown in full lines.

I claim:

The ornamental design for a lamp, substantially as shown and described.
